UNITED STATES PATENT OFFICE

155,927

DESIGN FOR A COMBINED IDENTIFICATION PLATE AND MONEY CLIP

Edgar Rothkrug, New York, N. Y.

Application March 16, 1948, Serial No. 145,144

Term of patent 7 years

(Cl. D74—2)

To all whom it may concern:

Be it known that I, Edgar Rothkrug, a citizen of the United States of America, residing in New York city, county of New York, and State of New York, have invented a new, original, and ornamental Design for a Combined Identification Plate and Money Clip, of which the following is a specification, reference being had to the accompanying drawing, forming part thereof, wherein:

Figure 1 is a front elevational view of a combined identification plate and money clip, showing my new design.

Figure 2 is a bottom edge elevational view.

Figure 3 is a rear elevational view.

Figure 4 is a view similar to Figure 1 showing the identification plate in partially separated position from the money clip.

The characteristic features of the combined identification plate and money clip reside in the portions shown in solid lines.

I claim:

The ornamental design for a combined identification plate and money clip, substantially as shown and described.

EDGAR ROTHKRUG.
